CLAIM

I claim the ornamental design for a waterslide run-out bowl, substantially as shown.

DESCRIPTION

FIG. 1 is a perspective view of the waterslide run-out bowl.

FIG. 2 is a top plan view of the waterslide run-out bowl.

FIG. 3 is a front elevation view of the waterslide run-out bowl.

FIG. 4 is a right side elevation view of the waterslide run-out bowl.

FIG. 5 is a left side elevation view of the waterslide run-out bowl.

FIG. 6 is a back elevation view of the waterslide run-out bowl; and,

FIG. 7 is a bottom plan view of the waterslide run-out bowl.
